COATED SECURITY CABLE AND LOCK ASSEMBLY

Basil D. Proskin, 4858 N. Natoma Ave.,
Chicago, Ill. 60656

Filed Oct. 31, 1975, Ser. No. 627,708

Term of patent 14 years

Int. Cl. D8—07

U.S. CL. D8—113

FIG. 1 is a perspective view of a coated security cable and lock assembly embodying my new design;

FIG. 2 is a front elevational view of the coated security cable and lock assembly;

FIG. 3 is a top plan view of the coated security cable and lock assembly; and

FIG. 4 is an end elevational view of the coated security cable and lock assembly.

I claim:

The ornamental design for a coated security cable and lock assembly, substantially as shown.
